UNITED STATES PATENT OFFICE.

GEORGE B. KOHLER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

CAR-WINDOW.

1,162,494.

Specification of Letters Patent. Patented Nov. 30, 1915.

Application filed February 9, 1914. Serial No. 817,697.

To all whom it may concern:

Be it known that I, GEORGE B. KOHLER, a citizen of the United States, residing in Philadelphia, Pennsylvania, have invented 5 certain Improvements in Car-Windows, of which the following is a specification.

The object of my invention is to provide a car window sash with a ventilating supplemental sash which forms part of the upper sash so that it can be opened to provide 10 ventilation at the side of a car.

The invention also relates to certain improvements in the detail construction of the means for hinging the upper sash to the 15 lower sash and the supplemental sash to the lower sash.

The invention also relates to the means for retaining the supplemental sash in position in the upper sash and also to providing 20 means for deflecting the air as it passes through the ventilating opening.

In the accompanying drawings: Figure 1 is a transverse sectional view of a portion 25 of a car frame at the window opening, showing the sash in the closed position; Fig. 2 is a detached perspective view showing the upper sash and a portion of the lower sash with the supplemental sash closed; Fig. 3 is a vertical sectional view through the upper 30 sash and the supplemental sash; Fig. 4 is a vertical sectional view showing the supplemental sash in the open position; Fig. 5 is an enlarged sectional view, showing the latch for retaining the supplemental sash in 35 the closed position; Fig. 6 is a vertical sectional view of the hinged joint of the sash; Fig. 7 is a sectional view on the line *a—a*, Fig. 6; Fig. 8 is a detached perspective view of the hinge plate and the pivot for the supplemental sash; Fig. 9 is a view of the hinge 40 plate for the upper sash; Fig. 10 is a detached perspective view of the upper portion of the lower sash at the hinge; Fig. 11 is a detached perspective view of the latch 45 for retaining the supplemental sash to the upper sash; Fig. 12 is a detached perspective view of the pivoted stop to limit the movement of the supplemental sash; Figs. 13 and 14 are sectional views on the line 50 *b—b*, Fig. 2, showing the supplemental sash closed and open and the stop for limiting the movement; Fig. 15 is a sectional plan view on the line *c—c*, Fig. 5, showing the latch; and Fig. 16 is a detached perspective 55 view of the deflector.

In the present instance, 1 is the side frame of a car.

2 is the roof structure of the ordinary type.

3 is the roof panel.

4 is the guide rail for the sash when it is raised.

5 is a guard rail for preventing the supplemental sash from swinging in the event of being raised without being fastened.

6 is the lower sash of the ordinary construction and 7 is the upper sash. These two sashes are connected by a rib and recess joint, the rib 8 being on the lower sash and the recess 9 being on the upper sash, as 70 clearly illustrated in Fig. 3. The two sashes are of metal, in the present instance, filled with wood, or other suitable material, but the sash may be made entirely of metal if desired. A sash of this type does not allow 75 for ventilation at the upper part. The usual practice is to raise the entire sash and to allow the air to enter through the lower portion of the window, which is objectionable. Ventilators in the roof of cars of this 80 construction are provided, but in many cases it is desirable to provide means for opening the sash at or near its upper end and this is accomplished by providing a supplemental sash 10, which is mounted in the upper sash, 85 in the present instance, and is arranged to swing on the same pivot so that, when it is necessary, the supplemental sash can be 90 swung into the car, as illustrated by dotted lines Fig. 1. This affords the necessary ventilation at the side of the car near the top.

The hinge for the sash is clearly illustrated in Figs. 6 to 10 inclusive, and consists of a combined hinge for the upper sash 7 and the supplemental sash 10. The upper sash 7 has a frame having a cross piece 11 and two side members 12. These side members extend to and are shaped to fit the round upper edge 8 of the lower sash 6. The supplemental sash is quadrangular in shape and has a recess 9 for the rib 8 of the lower sash and snugly fits between the side members and the cross member 11 of the upper sash. Secured to each lower corner of the supplemental sash is a hinge plate 13, made as clearly shown in Fig. 8, having a right angled section 14 carrying the pivot 15. This pivot extends through the opening in the plate 16 secured to the side members 12 and into the opening 17 in the side of the 110

upper corner of the lower sash 6. The plate 16 is offset to accommodate the portion 14 of the plate 13 and each upper corner of the lower sash is notched to receive both plates 5 so that they will be flush, as illustrated in Fig. 6, to allow the two sashes to travel in the guideways. By using a single pivot for the upper and the supplemental sash, the thickness of the sash is not increased, nor is 10 the meeting rail increased in width.

In order to adjust the supplemental sash 10, when in the open position, I provide a stop 18, Figs. 12, 13 and 14, which is pivoted to the said sash 10 and engages the side 15 members 12, they being cut away to allow for the movement of the stop. The stop is controlled by a spring and has two notches so that it can engage the edge of the cut in the member 12 and hold the supplemental 20 sash in either of two positions. To hold the supplemental sash in the closed position, I may use the latch illustrated in Figs. 2, 5, 11 and 15.

20 is a plate, recessed at 21, for the latch bolt 22 having a beveled edge so that it can be forced past the keeper 23 on the upper sash 7, Fig. 2.

24 is a rod bent to form an arm 25, which enters a recess 26 in the bolt 22 so that 30 when the rod is turned the bolt can be raised and lowered. Secured to the rod is a flat arm 27 which rests in the recess 28 in the upper sash and on the rod is a coiled spring 29 which tends to raise the bolt 22 so that 35 when the supplemental sash is closed the bolt rests back of the keeper 23. The plate 20 and its latch mechanism is mounted in a recess in the upper end of the supplemental sash and is inclosed by the metal 40 frame of the sash. The metal frame has an opening for the bolt and for the operating arm 27.

In order to direct air through the opening and into the car, I provide a deflector 30, 45 which is pivoted at 31 to the car frame and rests on the upper edge of the upper sash when the sash is closed. The deflector is cut away to clear the lip 32 of the guide. This deflector prevents the air from passing

into the space between the roof of the car 50 and the ceiling panel.

While I prefer to mount the supplemental sash on the same pivot as the upper sash, this construction may be modified without departing from the essential features of the 55 invention.

Though the sash is illustrated at the side of the car, it will be understood that it may be located at any position desired, depending upon the type of the car to which the 60 invention is applied.

I claim:

1. The combination in a sash structure, of a lower sash; an upper sash and a supplemental sash mounted in the upper sash; 65 pivots common to the upper sash and to the supplemental sash and engaging the lower sash.

2. The combination in a sash structure, of a lower sash having a round upper edge; 70 an upper sash having a cross bar and side members, the lower ends of the side members being recessed to fit the rounded upper edge of the lower sash; a supplemental sash mounted in the upper sash and having a 75 recess into which the rounded upper edge of the lower sash extends; with a pivot common to the upper sash and to the supplemental sash and arranged to swing on the lower sash.

3. The combination of a lower sash; an upper sash having a cross bar and side members; a perforated pivot plate secured to the lower end of each of said side members; a supplemental sash mounted in the 85 upper sash and having pivot plates; pins extending through the openings in the plates of the upper sash and into the lower sash so that the upper sash and the supplemental sash can swing on the same pivot. 90

In testimony whereof, I have signed my name to this specification, in the presence of two subscribing witnesses.

GEORGE B. KOHLER.
